CLAIM

The ornamental design for a wire clamping tool, as shown.

DESCRIPTION

FIG. 1 is a perspective view of the wire clamping tool taken from the front, top and one side showing my new design;

FIG. 2 is a perspective view thereof taken from the bottom, rear and opposite side;

FIG. 3 is a side elevational view thereof;

FIG. 4 is a top plan view thereof;

FIG. 5 is a front elevational view thereof; and

FIG. 6 is a rear elevational view thereof.
